(57) **CLAIM**

We claim the ornamental design for a portable computer, as shown and described.

DESCRIPTION

FIG. 1 is a perspective view of a portable computer of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a perspective view thereof shown in an open position;

FIG. 9 is a front view thereof shown in an open position;

FIG. 10 is a rear view thereof shown in an open position;

FIG. 11 is a first side view thereof shown in an open position;

FIG. 12 is a second side view thereof shown in an open position;

FIG. 13 is a top view thereof shown in an open position;

FIG. 14 is a bottom thereof shown in an open position; and,
FIG. 15 is a perspective view thereof shown in an alternate position.

The broken line showing of portable computer is included for the purpose of illustrating environment and forms no part of the claimed design.
